DESIGN FOR A CRADLE TOY OR SIMILAR ARTICLE

Seymour Tharler, Leominster, Mass., assignor to
Zadek Feldstein Co., Inc., New York, N. Y., a
corporation of New York

Application November 15, 1947, Serial No. 142,549

Term of patent 14 years

(Cl. D34—15)

To all whom it may concern:

Be it known that I, Seymour Tharler, a citizen of the United States, residing at Leominster, in the county of Worcester and State of Massachusetts, have invented a new, original, and ornamental Design for Cradle Toy or Similar Article, of which the following is a specification, reference being had to the accompanying drawing, forming part thereof.

In the drawing:

Fig. 1 is a front elevational view of a cradle toy or similar article, showing my new design.

Fig. 2 is a bottom view of the same;

Fig. 3 is a fragmentary end elevational view.

I claim:

The ornamental design for a cradle toy or similar article, as shown.

SEYMOUR THARLER.
